CLAIM

(51) **LOC (8) Cl.** **14-01**

The ornamental design for a digital audio disk player, as shown and described.

(52) **U.S. Cl.** **D14/156**

DESCRIPTION

(58) **Field of Classification Search** D14/135–136,

FIG. 1 is a front view of a digital audio disk player;

D14/156–157, 168, 197–198, 188, 257, 258;

FIG. 2 is a rear view thereof;

360/99.02, 99.07; 369/75.11, 75.21, 77.21,

FIG. 3 is a left-side thereof;

369/77.11; 720/612, 619, 647, 655; 455/344,

FIG. 4 is a right-side view thereof;

455/347–351

FIG. 5 is a top view thereof;

See application file for complete search history.

FIG. 6 is a bottom view thereof;

(56) **References Cited**

FIG. 7 is a perspective view thereof; and,

U.S. PATENT DOCUMENTS

FIG. 8 is another perspective view thereof showing the tray in an opened condition.
